UNITED STATES PATENT OFFICE.

ROBERT C. STUBBS, OF DALLAS, TEXAS.

MACHINE FOR MAKING COMPRESSED CONCRETE.

Application filed January 27, 1927. Serial No. 164,094.

My invention relates to improvements for laying or constructing pavements, and more particularly to means for laying compressed concrete pavement which requires distinctively different design of transmitting unit for accomplishing a distinctively different result. The improved transmitting unit is adapted for use in compressing plain concrete, mixed and placed and struck to grade, which is highly plastic, containing relatively high mortar content extending to the surface. Other objects and advantages will be fully explained in the following description and the invention will be more particularly pointed out in the claims.

Reference is had to the accompanying drawings which form a part of this application.

Figure 1 is a perspective view of a vibrating machine to which is applied the improvement hereinafter set forth.

Fig. 2 is a broken perspective view of the stringers or holders and the compressing plates.

Fig. 3 is a vertical cross-section of the devices shown in Fig. 2.

Fig. 4 is a longitudinal section of the out-of-balance element.

Fig. 5 is an end elevation of the same, showing the position of the parts for obtaining the maximum out-of-balance effect.

Fig. 6 is the opposite end from that shown in Fig. 5, showing the position of parts for obtaining partial out-of-balance effect.

Fig. 7 is an end elevation of the same, showing the position of parts for obtaining neutral effect of the out-of-balance element.

Fig. 8 is a detail view of devices for shifting the gear.

Similar characters of reference are used to indicate the same parts throughout the several views.

The machine has a motor provided with driven fly-wheels 1 and 2 and a shaft 3 therefor which is journaled in a frame 4. The motor is provided with a crank-case 5. The machine is provided with out-of-balance elements which are mounted on and operated by a shaft 6 which is journaled in frame 4. The out-of-balancing elements include an outer cylinder provided with a weighted side 7 and a light side 8. The inner cylinder has a weighted side 9 and a light side 10. The out-of-balancing elements include a friction wheel 14 which

is journaled in a yoke lever 15 which is carried by a fulcrum 16 which is mounted in the frame 4. The yoke 15 is used to hold the wheel 14 in mesh or against the face of the wheel 1 so that the wheel 14 will be driven by the wheel 1. The yoke 15 is provided with a handle 18 for operation of the yoke and for adjusting the wheel 14.

The vibrations are created by the inner and outer cylinders and transmitted to the frame 4 and from the frame 4 the vibrations are transmitted through rollers 21. The shafts 22 of the rollers 21 are journaled in bearings 23 which are rigid with the frame 4. The rollers 21 transmit the vibrations to the transmitting unit which consists of a device in the nature of a platform composed of stringers 24 which are so arranged as to permit air and excess water and mortar to escape from the concrete or plastic mass which is being treated with the pressure and vibrations.

The inner cylinder may be keyed to the shaft 6 as shown in the drawings so that it will revolve with the shaft 6. The outer cylinder may be held at any required point of adjustment relative to the inner cylinder by a collar 11, which is rigid with the inner cylinder and is provided with a corrugated or notched periphery, and by a dog or plunger 12 which is yieldably mounted on a spoke of the cylinder and adapted to engage any one of the corrugations or notches in the collar 11. The dog 12 is carried by a spring 13 which is attached to the spoke of the outer cylinder. The cylinder out-of-balance elements may be returned to normal position by the involute spring 19. A brake shoe 20 is provided for further controlling the speed of the cylinder out-of-balance element.

The machine, as above described, is adapted for laying or constructing types of paving known as "Vibrolithic" and "Armorplated" paving. It requires something different to lay or construct compressed concrete paving. It is necessary to distinguish the two operations by understanding that in the operation of compacting or making compressed concrete, excess water and air only are to be expelled from the mass. No mortar is required or desired to be brought to the surface, it being clear that finishing mortar already exists at the top of the mass, and over-wet mortar is distributed throughout the en-

tire mass, and it is necessary that much of such water be driven from the mass and be permitted to escape at the surface as naturally there is no other means or avenue of escape 5 for excess water from the concrete slab spread upon the earth or prepared grade.

Therefore, the problem was to draw out the water and air without bringing the mortar up, or to squeeze out the water and to 10 compact the mortar in layers between the aggregate of the slab. The improvement shown in the accompanying drawing includes a metallic sheet or plate 26 which is attached to the stringers 24 of the former transmitting 15 unit. The sheet 26 has a plurality of perforations 27. The perforations 27 are relatively small and will permit only air and surplus water to rise up out of the concrete mass. The perforations 27 may be of various 20 sizes and shapes for accomplishing various forms of construction, but for laying paving the perforations are preferably as shown in the drawings. The perforations 27 are made by slitting the plate 26 and then pressing 25 the metal on one side of each slit upwardly, as shown in Figs. 2 and 3 to form baffles 28 to cause uprising water to be spread evenly and to prevent the water from being thrown upwardly on the operators. The 30 openings 27 are small as compared with the total area of the plate 26, the ratio of the area of the openings to the area of the plate being approximately one to fifty. The object is to make the openings 27 so small that 35 mortar will not pass through the openings but air and surplus water are allowed to escape. The plates 26 are supposed to be of metal and so thin that material from the plastic mass will not accumulate on the edges 40 of the metal and choke the passages. The baffles 28 direct the water forwardly. The machine is operated by manually moving the machine along the stringers 24 while the machine is being driven by the motor which 45 actuates the out-of-balance element. Vibrations caused by the operations of the out-of-balance element are transmitted through-

out the mass of the plastic which is being treated and the treatment is of the body of the mass without jumbling the parts except 50 the mere adjusting of the parts for a compaction and forcing out of water and air. The mortar will be compacted on the surfaces of the stone which constitutes the aggregate, but practically no mortar will pass through 55 the plate 26. The mortar and the aggregate will be solidified into a compressed concrete. With the compressing plate, such as is described above, a very high percentage of the surface mortar solids are compacted by the 60 great contact area of the plate rather than being forced out through the apertures 27.

What I claim, is:—

1. In a device for compressing concrete by means of vibrations; a plate adapted to be placed in contact with freshly laid plastic and provided with openings for escape of air and surplus water and provided with means for controlling the direction of the escaping air and water. 70
2. In a device for compressing concrete by means of vibrations; a plate adapted to be placed in contact with freshly laid plastic and provided with direction controlling openings for escape of air and surplus water 75 and provided with direction controlling openings for escape of air and water.
3. In a device for compressing concrete by means of vibrations; a plate adapted to be placed in contact with freshly laid plastic 80 and provided with openings for escape of air and surplus water and means associated with said openings for spreading the water in predetermined directions.
4. A device of the character described for 85 making compressed concrete comprising a plate for applying to a mass of freshly laid concrete and provided with openings for escape of air and surplus water and baffles associated with said openings for controlling 90 the direction of the escaping water.

In testimony whereof, I set my hand, this 24 day of January, 1927.

ROBERT C. STUBBS.
